UNITED STATES PATENT OFFICE.

DAVID KUPERMAN, OF NEW YORK, N. Y.

HINGED SPRING-WIRE MATTRESS.

1,214,187.

Specification of Letters Patent. Patented Jan. 30, 1917.

Application filed October 19, 1915. Serial No. 56,678.

To all whom it may concern:

Be it known that I, DAVID KUPERMAN, a citizen of the United States, residing at 180 East Houston street, New York, county of New York, and State of New York, have invented certain new and useful Improvements in Hinged Spring-Wire Mattresses, fully described and represented in the following specification and the accompanying drawings, forming a part of the same.

The object of this invention is to furnish a convenient means of hinging one edge of a spring-wire mattress to the frame of a bedstead so that the mattress can be tipped up to facilitate the cleaning of the floor beneath the bed. By suitably hinging the edge of the mattress, it may be readily tipped up and remain in an erect position during the sweeping or scrubbing of the floor. In such constructions, it has been common to provide the frame of the spring mattress with special hinged members to operate in connection with corresponding members upon the side-bar of the bedstead, but in the present construction any modification of or attachment to the frame of the spring mattress is avoided, by utilizing the brackets at the corners of the spring mattress-frame as hinged members for jointing to the side-bar of the bedstead.

The corner brackets in the present invention have flat flanges which project transversely at both ends of the spring-mattress-frame, and such flanges are converted into hinges by merely perforating them to admit a hinge-pin, and mounting forked bearings upon the side-bar of the bedstead to receive the flanges, which are jointed thereto by extending a pin or bolt through both. Such hinging of the two frames together is effected at one side only of the bedstead, and permits the opposite edge of the spring mattress to be raised to a vertical position, in which the forked bearing supports it while cleaning beneath the bed.

The invention will be understood by reference to the annexed drawing, in which—

Figure 1 is a side view of the bedstead and spring mattress, both being broken away at the middle of the length to shorten the view; Fig. 2 is a cross section on line 2—2 in Fig. 1 looking in the direction of the arrow marked 2; Fig. 3 is an end view of one of the corner brackets, side views of which are shown in Fig. 1; Fig. 4 is an end view of one of the forked bearings; and Fig.

5 is a perspective view of one of said bearings. Fig. 6 is an end view of the hinged connection of the wire mattress with the bedstead, the mattress being tipped up-
wardly.

a, a' designate the head and foot of the bedstead, which are connected by tie-bars *b*. *d* is the wire of the spring mattress stretched between end-bars *d'*, which are extended transversely between the upwardly projecting arms *c* of the corner brackets. The body of the spring wire is omitted in Fig. 2, and only the tension-springs *c'* are shown, by which the mattress wire is commonly held under tension. These brackets are formed with sockets *e* for the side-bars or braces *e'*, which with the brackets and end-bars *d'* form a square frame on which the spring wire *d* is stretched. The heads or tops of the brackets are connected to the sockets *e* by flat flanges *f* at right-angles to the sockets, which flanges by forming bolt-holes *g* therein operate directly as hinge-members for the wire mattress-frame. The flanges are made with a vertical outer edge even with the outer edge of the spring wire mattress, and with a horizontal edge at the bottom which is adapted, at one side of the bed, to rest upon the angle tie-bar *b*, as is shown in Fig. 6.

Corresponding hinge-members or bearings are fitted to one of the tie-bars *b* of the bedstead, which are commonly made of angle-iron as shown in Fig. 2. Each bearing in such case made with an angle-shaped foot-piece *h* to fit the top and outer side of the tie-bar *b*, and with a hook *h'* to fit the inner edge of such tie-bar.

Two bearing-plates *i* project upwardly from the foot-piece at a suitable distance apart to admit the flange *f*, and each bearing-plate is perforated with a bolt-hole *g'* which, with the bolt-hole *g*, receives a hinge-bolt. The foot-piece of such angle-bearings can, by tipping it, be applied to an angle-iron like the tie-bar *b*, and is thus a removable attachment which can be applied or removed at pleasure, and which needs no fastenings, as the hook holds the bearing firmly in place when the weight of the mattress rests upon it.

To support the spring mattress when tipped upwardly as shown by dotted lines in Fig. 2, the bolt-hole *g* is made in the lower corner of the flange *f* at one side of the socket, at the same distance from the outer

edge of the bracket as the bolt-hole g' is located above the top side of the foot-piece h , and when the mattress is swung upwardly the outer edge of the bracket becomes horizontal and contacts with the foot-piece, and supports the wire mattress in an erect position. Such contact is secured by locating the hole g' at one side of the socket, as described.

10 Fig. 2 represents the wire mattress in full lines in its normal position, being hinged at the right-hand side to one bedstead tie-bar b , and at the left-hand side having the lower edge of the flange f resting directly upon the other tie-bar b .

15 Fig. 6 shows the hinged connection of the mattress with the tie-bar b , upon a larger scale than Fig. 2, and the mattress tipped upwardly and supported by the contact of the flange f with the foot-piece h .

20 Many spring mattresses are in use with corner brackets of the shape shown in the drawing, and can be readily hinged to the side-frame of the bedstead by merely forming the hole g in such bracket flanges, and applying the hinged bearings to the side-bar of the bedstead.

25 The making of any separate hinge-part for the spring mattress-frame is thus avoided, and a hinged connection between the spring mattress-frame and the bedstead is secured at the smallest possible expense.

Having thus set forth the nature of the invention what is claimed herein is:

30 The combination, with a spring wire-mattress having corner brackets connected by side-bars, and each bracket being formed with a socket for the side-bar and a flat flange transverse thereto and projected at one side of the socket and the flange having 35 a bolt-hole in its lower corner at one side of the socket, of bearings pivoted to the bolt-holes in said flanges and having each a foot-piece adapted to detachably engage the tie-bar of the bedstead, and the outer edge 40 of the flange being adapted to rest upon the foot-piece and maintain the mattress in a vertical position when the mattress is tipped upwardly, as and for the purpose set forth.

45 In testimony whereof I have hereunto set my hand.

DAVID KUPERMAN.
